GOLF BAG

Application filed June 1, 1931. Serial No. 541,460.

This invention relates to bags especially adapted for use in carrying golf clubs.

The invention forming the subject of this application contemplates a golf bag in which one longitudinal side wall thereof is gently curved in contrast to the sharply curved opposite longitudinal wall of the bag to increase the bag in cross-sectional area toward the gently curved side wall of the bag to allow the irons used in golf to lie side-by-side against the gently curved wall for convenient selection and removal, it being noted that the edge portions of the gently curved side of the bag are curved to merge into the more sharply curved opposite side wall of the bag to define rounded corners preventing the irons from massing in the corners of the bags.

Also, the provision of a gently curved or nearly flat longitudinal wall of the bag provides a means by which the bag is held against turning when laid on rolling ground, or against a tee box, a tree, a tee rack or other upright support.

Another feature of the invention resides in the provision of means by which the wooden and iron clubs may be held separated when the hood employed on some golf bags is in place over the heads of the clubs.

A further object is to provide a golf bag which while embodying the foregoing advantages particularly, the means by which the clubs are caused to remain side-by-side in a gradually curved row for convenient selection, will not differ radically in mode of manufacture or appearance from conventional golf bags and will, therefore, be more acceptable to the public.

Other objects and advantages will be apparent during the course of the following description.

In the accompanying drawing, forming a part of this application and in which like numerals are employed to designate like parts throughout the same,

Figure 1 is a perspective of the improved bag in an upright position.

Fig. 2 is a fragmentary perspective of the bag in a nearly horizontal position, the view illustrating the irons side-by-side against the previously described gently curved side wall

so that the clubs may be conveniently selected and removed from the bag.

Figure 3 is an end view of the bag, the view being intended to illustrate that what might be said to be the nether longitudinal wall of the bag is gently curved in contrast to the much more sharply curved opposite side wall of the bag to provide first for the arrangement of the irons in a neatly curved row side-by-side and second, to cause the bag to remain in place when laid upon the ground or against an upright support, such for example, as a tree or a tee box.

Figure 4 is a fragmentary perspective of the bag illustrating the manner in which the wooden and iron clubs are held separate when the hood of the bag is in place over the clubs.

In the drawing, wherein for the purpose of illustration is shown a preferred embodiment of the invention, the numeral 5 generally designates a tubular bag which may, of course, be of either the flexible or ribbed type. The lower end 6 is preferably rigid and, if desired, may be provided with a boot 8 by which wear is resisted.

The bag 5 has the mouth thereof held firmly in the shape shown in Figure 3 by the provision of internal stiffening of any kind and as shown in Figure 3, one longitudinal side 10 of the bag is gently curved in contrast to the much more sharply curved opposite side wall 12 with the result that the bag and more particularly the club receiving compartment thereof is increased in cross-sectional area toward the gently curved wall 10, thereby allowing a generous number of irons 16 to be arranged side-by-side against the wall 10. It is important to observe that the curvature of the edge portions 11 of the wall 10 is increased as compared with the central portion of the side wall so that such edge portions are caused to merge into the side walls 12 and thereby form rounded corners; this being in contrast to certain other bags having flat side walls abruptly joining other side walls, with the result that the sharp corners thus defined allow the irons to mass therein.

A bag constructed in accordance with this invention may, of course, be equipped with

the usual carrying handle 20 and with a conventional strap 22, the latter providing simple means by which the bag may be suspended from the shoulder of a caddy or a player.

5 When the bag is carried either by the handle 20 or the strap 22 the iron clubs 16 will rest against the gently curved bottom side wall 10, side-by-side, and the rounded corners 11 will cause the irons to come sufficiently close together to accommodate such reasonable number of irons as may be placed in the bag without causing one iron to rest upon another. With the irons thus arranged side-by-side in a gently curved row, the same are 10 positioned for convenient selection and removal as distinguished from those bags in which the selection of clubs is interfered with by the haphazard arrangement of the clubs. As is known, some irons are longer 15 than others and the haphazard arrangement of the irons in the bag makes it inconvenient and some times aggravating to locate the desired club. In a bag forming the subject of this application, the arrangement of the clubs 20 in a neat row exposes all the clubs, regardless of the lengths thereof so that the selection of a particular club is greatly aided. This advantage has been found to appeal strongly 25 to those golfers who are disturbed by the vexacious delays incident to the location and the subsequent inconvenient removal of the 30 desired club.

Particular attention is directed to the fact 35 that the clubs are more or less self-positioning in row formation in the bag, this being true because of the gradual dip of the bottom wall 10 toward the longitudinal center thereof and thus even though the club is placed in the bag in a more or less hasty manner without 40 regard to its ultimate position therein, it will come to rest against the gently curved bottom wall with the weighted heads thereof depending by gravity, so that all the irons will assume the positions illustrated in Figure 2.

45 Of course, the provision of the gradually curved longitudinal bottom wall 10 is especially designed for arranging the irons neatly in a row because the irons far exceed the wooden clubs in number.

50 The wooden clubs 30 are held in the upper longitudinal side of the bag by a flexible strap 32 of any nature. A buckle 34 provides 55 a convenient means by which the effective length of the strap may be varied for the accommodation of the wooden clubs that are placed in the bag.

At this point, it might be noted that the 60 irons 16 are placed in that portion of the bag in which the cross-sectional area thereof is increased while the wooden clubs are held separate in that portion of the bag in which the cross-sectional area thereof is decreased.

65 A bag constructed in accordance with this invention may be provided with a hood 40

joined by stitching or other suitable means to the upper end portion of the bag and having a longitudinal incision adapted to be closed by a hookless or other fastener 42. The hood is provided adjacent its point of connection 70 with the bag with a pair of eyelets or apertures 46, adapted for the passage of the strap 32 so that, even though the hood is in position over the clubs as suggested in Figure 4, 75 the wooden and iron clubs will be held separate.

In use, the improved bag may be laid flatly upon the ground and the nearly flat or gently curved longitudinal wall 10 will hold the bag 80 against rolling. Also, when the bag is leaning against a tee box, a tree, or other upright support with the gently curved wall 10 against such support, the bag will be held in place.

As brought out in the opening paragraphs 85 of this specification, while a bag constructed in accordance with this invention has the foregoing substantial advantages, particularly the curved longitudinal side wall merging into the more sharply curved opposite wall of the bag to hold the clubs neatly in a row and to avoid sharp corners in which the clubs might mass, the bag is, nevertheless, 90 not radically different in appearance from conventional bags and therefore meets with more ready approval than would otherwise be the case, it being recognized that radical departures in the matter of appearance are 95 sometimes distasteful to the more sensitive and fastidious golfers because they dislike the attention focused on them by such radical departures in appearance.

100 It is to be understood that the form of invention herewith shown and described is to be taken merely as a preferred example of the same and that such minor changes and arrangement of construction of parts may be made as may remain within the spirit 105 of the invention and the scope of what is claimed.

Having thus described the invention, what is claimed is:

110 In a golf bag, a tubular body having a longitudinal wall forming a rest for golf clubs provided with a gradual transverse curvature, and a second wall curved opposite to the curvature of the first named wall and joined therewith, the junction of said first and second named walls being rounded to induce the lateral movement of the clubs toward the longitudinal center of said rest thereby preventing the massing of the clubs at the junction of the first and second named walls, the curvature of the rest being so gradual as to prevent the clubs massing at the center and resulting in the clubs being properly spaced from each other.

115 In testimony whereof I affix my signature.

120 THOMAS O. JOHNSEN. 130
